UNITED STATES PATENT OFFICE.

DANIEL BROWN, OF NEWARK, NEW JERSEY.

ACETYLENE-GAS LAMP.

SPECIFICATION forming part of Letters Patent No. 681,616, dated August 27, 1901.

Application filed February 20, 1901. Serial No. 48,048. (No model.)

To all whom it may concern:

Be it known that I, DANIEL BROWN, a citizen of the United States, residing at Newark, in the county of Essex and State of New Jersey, have invented certain new and useful Improvements in Lamps, of which the following is a full and complete specification, such as will enable those skilled in the art to which it appertains to make and use the same.

This invention relates to acetylene-gas lamps; and the object thereof is to provide a small lamp of this class which may be used as a bicycle-lamp, as a doctor's or surgeon's lamp, and for many other purposes where small lamps of higher illuminating power are required.

This invention is fully disclosed in the following specification, of which the accompanying drawings form a part, in which the separate parts of my improvement are designated by the same reference characters in each of the views, and in which—

Figure 1 is a side view of my improved lamp, and Fig. 2 is a central vertical section thereof. In the practice of my invention I provide a tube 5, which is provided at the top thereof with a cap 6 and at the lower end with a water-reservoir 7, detachably connected therewith in any desired manner, and said reservoir is provided at a predetermined distance from the top with a transverse closing-plate 8, in the center of which is a nozzle 9, which, as shown in the drawings, is closed by a cork or plug 10, but any suitable device may be employed for this purpose. The cap 6 of the tube 5 is largest at its lower end, and the central portion thereof is reduced, as shown at 11, and the top portion still more reduced, as shown at 12, and within the central reduced

portion 11 is placed a supplemental tube 13, the upper end of which is secured within said cap and between which and the tube 5 is an annular space 14, and the lower end of the tube 13 is closed by a cork or plug 15, provided with perforations 16, but the lower end of the tube 13 may be closed, however, in any desired manner, all that is necessary in this connection being to provide a suitable closure device having perforations. I also provide a central tube 17, which serves as a carbide-receptacle, and this tube is open at the lower end, and the upper end thereof is closed by a

plug 18, having perforations 19, but the upper end of said tube may be closed in any desired manner, all that is necessary in this connection being to provide a suitable closure device having perforations.

The cap 6 is removable from the outer tube 5, and the carbide-receptacle is removable from the inner tube 13, it being understood that the plug 15 is removable from the lower end of the tube 13 in order to remove the carbide-receptacle. In practice the carbide-receptacle is filled with carbide, as shown at 20. The burner-tube 21 passes through one side of the cap 6 and through one side of the tube 13, and this burner-tube is provided at the outer end thereof with a tip 22 and near said end with a reflector 23, and when the parts are connected, as shown and described, all that is necessary to start the generation of gas is to detach the reservoir 7, remove the cork or plug 10, and place said reservoir in position and invert the device. In this operation the water flows from the reservoir 7 into the main outer tube 5, and when said tube is full of water the reservoir is again connected with said tube, the plug 10 being first placed in the orifice 9 and the device held in an upright position. The water then flows through the plug 15 and mingles with the carbide in the carbide-receptacle 17, and gas is generated within and passes out through the plug 18 at the upper end of the carbide-receptacle and through the burner-tube 21 and may be ignited at the tip 22.

In practice I prefer to provide a number of the carbide-receptacles 17, each of the same being filled with carbide, and the party using this lamp may always have a number of said receptacles ready for use.

The operation of detaching the reservoir 7 and filling the tube 5 with water may be repeated as often as desired, and a new carbide-receptacle may be substituted for the exhausted one whenever necessary. A lamp made in this way will operate with a single carbide-receptacle, for about an hour and a half, as hereinabove stated, and a new carbide-receptacle may be inserted whenever necessary, or, if convenient, the old carbide-receptacle may be emptied and refilled.

The main outer tube or casing 5 is provided at one side with a hook or other device 24,

by which it may be suspended from any suitable support, and the entire device is simple in construction and operation and perfectly adapted to accomplish the result for which it is intended, and changes in and modifications of the construction described may be made without departing from the spirit of my invention or sacrificing its advantages.

Having fully described my invention, what I claim as new, and desire to secure by Letters Patent, is—

1. An acetylene-gas lamp, comprising in its construction an outer casing, an inner tube of the same diameter throughout its length within said casing, a cap surrounding the upper end of said outer casing and provided with a plurality of annular shoulders, one of which is adapted to engage the upper end of said inner tube and retain the same centrally of the outer casing, thereby providing an annular space between said inner tube and outer casing, a perforated closure in the lower end of said inner tube, a carbide-receptacle within said inner tube, means for supplying water to said carbide-receptacle, and a flame-tube communicating with said inner tube, substantially as described.

2. An acetylene-gas lamp, comprising in its

construction an outer casing, an inner tube within the same, a cap surrounding the upper end of said outer casing and provided with an annular shoulder adapted to engage the upper end of said inner tube and retain the same in position within said outer casing, thereby providing an annular space between the inner tube and the outer casing, the said annular shoulder of said cap at the same time serving to close the upper end of said annular space, whereby water placed in said space cannot enter the inner tube at the top, a carbide-receptacle within said inner tube, means for supplying water thereto, and a flame-tube penetrating said cap at a point on said annular shoulder, whereby the inner end of said tube communicates with the inner tube, and the outer end extends at right angles to the said outer casing and beyond the same, substantially as described.

In testimony that I claim the foregoing as my invention I have signed my name, in presence of the subscribing witnesses, this 16th day of February, 1901.

DANIEL BROWN.
